CLAIM

I claim the ornamental design for an electric converter, as shown and described.

DESCRIPTION

FIG. 1 is a perspective view of an ornamental design for the electric converter of the present invention, said perspective view showing the top, the front and the right side of the electric converter;

FIG. 2 is a perspective view of an ornamental design for the electric converter of the present invention, showing the top side of the electric converter;

FIG. 3 is a perspective view of an ornamental design for the electric converter of the present invention, said perspective view showing the bottom, the rear and the right sides of the electric converter;

FIG. 4 is a top view of the electric converter of the present invention;

FIG. 5 is a bottom view of the electric converter of the present invention;

FIG. 6 is a front view of the electric converter of the present invention;

FIG. 7 is a rear view of the electric converter of the present invention;

FIG. 8 is a right side view of the electric converter of the present invention; and,

FIG. 9 is a left side of the present invention.
